INVISIBLE SUSPENDER

Harry C. Lyons, Mount Vernon, N. Y.

Original application February 11, 1936, Serial No. 63,303. Divided and this application March 23, 1937, Serial No. 132,478

1 Claim. (Cl. 241—25)

My invention relates to a new and improved invisible suspender.

This invention is a division of my application Serial No. 63,303, filed February 11, 1936.

One of the objects of my invention is to provide 5 suspenders which are concealed by the shirt of the wearer and which will remain in effective engagement with the trousers, even when the wearer is sitting or stooping or moving his body in various ways.

Another object of my invention is to provide 10 a simple device which can be connected directly to the inside of the waistband of a pair of trousers.

Other objects of my invention will be set forth 15 in the following description and drawing which illustrate a preferred embodiment thereof, it being understood that the above statement of the objects of my invention is intended generally to explain the same without limiting it in any manner.

Fig. 1 is a sectional view showing one embodiment 20 of the invention.

Fig. 2 is a view similar to Fig. 1 and showing a 25 modification of the invention.

Fig. 3 is a sectional view on the line 3—3 of Fig. 2.

Fig. 4 is a view generally similar to Fig. 3 but showing another modification of the invention.

Fig. 5 is a sectional view on the line 5—5 of 30 Fig. 4.

Fig. 6 is a sectional view on the line 6—6 of Fig. 4.

Fig. 7 is a detail perspective view of one of the 35 parts which are included in the embodiment of Fig. 4.

Fig. 8 is a perspective view showing another of the parts which are included in the embodiment of Fig. 4.

Fig. 9 is a view similar to Fig. 8 but showing a 40 modification thereof.

Referring to the drawing, only the construction of the end-member of the suspenders and of its appurtenant elements is illustrated, as my 45 invention is principally concerned with this portion of the suspenders. The remaining conventional portions of the suspenders are not shown.

The end-member is designated by the reference 50 numeral 6 and said end-member can be made of elastic or non-elastic material.

Fig. 1 illustrates the shirt S and the waistband W of the trousers T, in combination with a fastening member 10. Said member 10 preferably 55 has a rectangular cross-section and said fasten-

ing member 10 may be made of elastic or non-elastic material.

As shown in Fig. 4, said member 10 is provided with buttonholes whereby its ends can be connected to buttons which are sewed to the inside of the waistband of the trousers T. Said member 10 can be connected to the waistband in any suitable removable manner.

Referring to Fig. 1, the material of the shirt S is bent to form a main bight or loop so that a portion of the material of the shirt enters a hook 15, and a part of said bight of the shirt also passes around and below the member 10.

The hook 15 is formed with a shoulder 16. The hook-member 15 can engage the fastening member 10 so that the trousers are properly supported.

Fig. 2 is generally similar to Fig. 1, save that Fig. 2 shows a hook-member 17, which has a shoulder 18 in its inner wall. Said shoulder serves as a lip to hinder the removal of the member 10 from the member 17, which otherwise might result from a downward movement of the member 17 relative to the member 10. Said shoulder is formed in the inner wall of said hook-member and said shoulder is laterally and outwardly directed.

In the embodiment shown in Fig. 2, the thickness of the member 10 is substantially equal to the opening in the hook-member 17, said opening being defined by the left-hand edge of the lip or shoulder 18 which is shown in Fig. 2 and the opposite wall of said hook-member 17.

The material of the shirt S acts to prevent the member 10 from being released from the member 17, when the member 17 is moved downwardly relative to the member 10. As shown in Fig. 2, the shoulder 18 forms a supplemental bight in the inner wall of the main bight of the shirt, and this supplemental bight substantially abuts the upper edge of member 10. Fig. 1 shows the outer wall of member 10 bent so as to provide an equivalent shoulder or constriction. However, the member 10 can be pushed upwardly so as to be squeezed past the lip 18, so that the shirt and the suspenders can be removed from the member 10, without making it necessary to move the member 10 longitudinally, relative to the hook-member.

Fig. 3 shows how a loop is formed in a part of the shirt fabric, so as to enter the hook-member 17.

Fig. 7 shows a U-shaped member 21, which is provided with inwardly bent wings 21a.

Tongues 22 are stamped out of the rear wall of the member 21, as shown in Fig. 7, leaving a

web 21b between said tongues 22. These tongues 22 are forced through the member 10, as shown in Fig. 6, and said tongues 22 thus clamp the member 21 permanently to the member 10.

5 The member 6 is provided with an enlarged portion 19, which has end wings 20. The enlarged portion 19 is slidable within the member 21, and the wings 20 prevent the member 21 from moving downwardly off the member 6.

10 In this embodiment a portion of the shirt is formed into a hollow T shaped loop which passes between the wings 21a of the member 21. In order to remove the shirt from the device, the member 6 is slid downwardly relative to the member 21, until the relatively narrow portion of said member 6, which is shown at the top of Fig. 8, is located within the member 21. In the position of the parts which is shown in Figs. 4-6, the enlarged portion 19 is located within the member 21, thus holding the shirt in position. The member 21 may be connected to the waistband W in any suitable manner, so as to eliminate the members 10.

15 Fig. 9 is essentially the same as Fig. 8, save that Fig. 9 shows a member 6 of tapered shape so that it has an enlarged bottom end 23. The member 21 is the same as the member 21 shown in Fig. 7, and the downward movement of member 21, relative to member 6, is limited by the 20 tapered shape of member 6.

25 The member 10 can be made of any suitable fabric or other flexible material.

Referring to the embodiment which is illustrated in Figs. 6-8, the member 19 fits with sufficient snugness within the member 21, so as to hold the loop of the shirt frictionally in position.

5 I have shown preferred embodiments of my invention, but it is clear that numerous changes and omissions can be made without departing from its spirit.

10 I claim:

15 In combination with the waistband of a pair of trousers, a holding member connected at spaced points to the inner surface of said waistband, suspenders having a hook-member at an end thereof, said hook-member being shaped and adapted to be passed between the inner surface of the waistband and said holding member so that said holding member is engaged by said hook-member, and a shirt located exterior to said suspenders, said shirt having a portion thereof located in said hook-member and between said hook-member and said holding member, said holding member having a vertically elongated cross-section with a longitudinally extending upper edge, the opening of said hook-member being constricted, said constriction being so located that said hook-member will clamp a portion of the material of the shirt against said longitudinally extending upper edge, to hinder separation between said holding member and said hook- 20 member.

25 30 HARRY C. LYONS.
